UNITED STATES PATENT OFFICE.

JOHN EDENS, OF DAVENPORT, IOWA, ASSIGNOR TO H. F. BRAMMER MANUFACTURING COMPANY, OF DAVENPORT, IOWA, A CORPORATION OF IOWA.

OPERATING-GEARING FOR WASHING-MACHINES.

1,093,982.

Specification of Letters Patent.

Patented Apr. 21, 1914.

Application filed September 19, 1912. Serial No. 721,116.

To all whom it may concern:

Be it known that I, JOHN EDENS, a citizen of the United States, and a resident of Davenport, in the county of Scott and State 5 of Iowa, have invented certain new and useful Improvements in Operating-Gearing for Washing-Machines and the like; and I do hereby declare that the following is a full, clear, and exact description thereof, 10 reference being had to the accompanying drawings, and to the letters of reference marked thereon, which form a part of this specification.

This invention relates to an improvement, 15 in operating mechanism for washing machines and the like and consists of the matters hereinafter described and more particularly pointed out in the appended claims.

The invention is shown herein as applied 20 to a washing machine of familiar type, consisting of a tub having a hinged top upon which is supported a shaft which depends into the tub and is provided at its lower end with a dolly or dasher adapted for rotary, 25 oscillatory movement by means of which the clothes and water are first stirred in one direction and then in the opposite direction.

The operating mechanism is of the lever actuated, high-speed gear type, and includes 30 a prime-moving lever fulcrumed to the top of the support, in this case a tub, and a fly-wheel carried under the tub, together with mechanism for changing the oscillatory movement of the lever on the one hand, 35 into a rotary oscillatory movement of the dolly shaft, and on the other hand into a continuous rotary movement of the fly-wheel.

The advantages of my improvement will appear as I proceed with my specification.

40 In the drawings:—Figure 1 is a view in side elevation (with a part broken away) of a washing machine provided with my improved operating mechanism. Fig. 2 is a top plan view of the same. Figs. 3 and 4 represent detail sectional views on an enlarged scale, taken in vertical planes indicated, respectively, by the lines 3—3 and 4—4 of Fig. 1. Fig. 5 is a view representing a partial vertical section taken in a plane indicated by line 5—5 of Fig. 2. Fig. 6 represents a detail sectional view on an enlarged scale taken in a plane indicated by line 6—6 of Fig. 2. Figs. 7 and 8 are de-

tail sectional views on an enlarged scale to be referred to more particularly later.

55

Referring now to that embodiment of my invention illustrated in the drawings, 10 indicates a support, in this case a tub of usual form mounted upon upright legs 11, 11. The said legs are rigidly braced apart by diagonally arranged cross-bars 11^a, 11^a. The support has a hinged member, in this case a lid 10^a connected by hinges to a horizontal fixed board 10^b forming a part of the top closure of the tub.

60

12 indicates a dolly or beater (see Fig. 3) which is non-rotatively connected to a dolly-shaft 13 that is rotatively suspended from the top of the hinged member or lid 10^a of the tub. The shaft 13 has bearing in a 70 sleeve 14 which projects through an aperture in the lid of the tub and which, as shown, is made integral with a horizontal base-plate 14^a attached to the top surface of the lid. A spur-gear 13^a is fixed to the up- 75 per end of the shaft 13.

65

15 indicates a horizontal, longitudinally reciprocating, rack-bar having on one lateral edge rack-teeth 15^a which engage the spur-gear 13^a on the dolly-shaft. Said rack-bar 80 slides in guides or ways comprising lugs 14^b, 14^b, rising from the base-plate 14^a and plates 14^c, 14^c attached to said lugs.

85

16 indicates a lever adapted to swing in a vertical plane and fulcrumed between upright arms 14^c, 14^c made integral, as shown with the base-plate 14^a.

85

17 indicates a link connecting one arm 16^a of the lever 16 with a horizontal laterally extending lug 15^b fixed on the rack-bar 15. 90 The lever 16 is provided with a socket member 16^b to receive an operating handle 16^c by means of which it may be oscillated so as to impart a longitudinal, reciprocating movement to the rack 15.

95

17^a indicates a vertically arranged, rotative shaft mounted at the side of the tub and having bearing support in horizontal arms 18^a, 18^a formed on a bracket 18 which is secured to the side wall of the tub body. 100 I prefer to provide antifriction bearings for the shaft 17^a which may be constructed as clearly illustrated at 19 in Fig. 7, the said figure showing a vertical, central section through one of the bearings. To the upper 105 end of the shaft 17^a is secured a horizon-

tal disk 20 which is provided in its top face near its periphery with a plurality of spaced recesses or apertures 20^a arranged in a circle.

21 indicates a pitman pivotally connected 5 at its inner end to one end of the rack-bar 15. The outer end of the pitman 21 carries a vertical pin 21^a which is adapted for engagement with one of the apertures or recesses 20^a. When the rack-bar 15 is reciprocated, it imparts through the pitman 21 a continuous, rotary movement to the disk 20 and shaft 17.

Below the horizontal bottom wall of the tub or support and, as shown, in vertical 15 alignment with the dolly-shaft 12 is located a vertical shaft 22. The said shaft 22 is rotatively supported at its top and bottom ends in brackets 23, 24, respectively, secured to the bottom of the tub or support 20 and to the cross-bars 11^a, 11^a, at their intersection. I preferably provide antifriction bearings for the shaft at these points which may be such as indicated at 25 in Fig. 8, the said figure illustrating a vertical central section of the bearing 23 at the top end of the shaft.

26 indicates a fly-wheel fixed on the shaft 22 near its upper end and 27 a pulley fixed on said shaft near its lower end. A pulley of 30 larger diameter 28 is fixed to the lower end of the vertical shaft 17 at the side of the tub and an endless band or belt 29 operatively connects the two pulleys 28, 27, so that the continuous rotary movement of the said shaft 17 will be communicated to the shaft 21 and thence to the fly-wheel which is caused to rotate at high speed.

The operation of my improved gearing is apparent from the foregoing description. 40 The oscillation of the prime-mover, that is to say, the lever 16 will, through the link connecting it with the rack-bar 15, impart an oscillatory rotary movement to the dolly-shaft and at the same time the pitman 21 connecting the outer end of the rack-bar 15 with the disk 20 will impart a continuous rotary movement to the upright shaft 17. The shaft 17 will then impart a continuous rotary movement to the fly-wheel by means 50 of the pulleys 28, 27 and the belt 29.

The advantage of using a belt-drive is apparent, the same being noiseless and in addition, if for any reason it is desired to stop the motion of the dolly-shaft, the handle of 55 the prime moving lever is grasped to stop the movement of the same and should the momentum of the fly-wheel be such as to continue its rotation, the belt will slip on the small pulley 27, without producing an undue 60 strain or jar on the mechanism.

In raising the lid 10^a of the tub for any purpose, the pitman 21 will be automatically disengaged from its connection with the disk 20 and to prevent its falling back too far 65 toward the hinges of the lid when thus disen-

gaged, I provide upon the base-plate 14^a a vertically arranged transverse flange 14^c. That part of the said flange nearest the hinges of the tub-lid 10^a is raised above the normal plane of the link 21 to form a lug 70 14^d against which the pitman rests when the tub-lid is in raised position. In order that the pitman 21 may be properly engaged in one of the apertures in the disk 20 when the tub-lid is closed, I preferably provide upon 75 said link a knob 21^b to be grasped in shifting the pitman into such position that the pin 21^a carried thereby will engage in one of the apertures or recesses in the disk 20.

While in describing one embodiment of 80 my invention I have referred to certain details of mechanical construction and arrangement, it is to be understood that the invention is in no way limited thereby except as pointed out in the appended claims. 85

I claim as my invention:—

1. Operating mechanism for washing machines and the like comprising, in combination with an operating shaft capable of rotary reciprocating movement, a gear fixed 90 to said shaft, a reciprocable rack-bar in mesh with said gear, a hand-lever for actuating said rack-bar, a second shaft spaced from and parallel to said operating shaft, means connecting said second shaft with 95 said rack-bar for continuously rotating said second shaft, a fly-wheel located below said operating shaft and a pulley and belt connection between said second shaft and said fly-wheel. 100

2. Operating mechanism for washing machines and the like comprising, in combination with a support including a movable top member, an operating shaft capable of rotary reciprocating movement carried by said 105 top member, a gear fixed to said shaft, a reciprocable rack-bar carried by said top member in mesh with said gear, a hand-lever fulcrumed on said top member for actuating said rack-bar, a second shaft rotatively mounted at the side of said support, means connecting said second shaft with said rack-bar for continuously rotating said second shaft, said means including a device adapted to be detached when said top member is 110 raised, a fly-wheel located below said support and a pulley and belt speed increasing connection between said second shaft and said fly-wheel. 115

3. Operating mechanism for washing machines and the like comprising, in combination with a support, an operating shaft capable of rotary reciprocating movement, a gear secured to said shaft, a reciprocable rack-bar in mesh with said gear, a hand-lever for actuating said rack-bar, an intermediate shaft located at the side of said support extending parallel to said operating shaft, a crank-disk secured to the upper end of said intermediate shaft, a pitman for con- 120 125 130

necting said rack-bar with said crank-disk, a fly-wheel rotatively mounted below said support, and a belt and pulley speed-increasing connection between the lower end 5 of said intermediate shaft and said fly-wheel.

4. Operating mechanism for washing machines and the like comprising, in combination with a support including a movable top member, a vertical operating shaft capable 10 of rotary reciprocatory movement carried by said top member, a gear secured to said shaft, a horizontal, reciprocable rack-bar carried by said top member in mesh with said gear, a hand-lever fulcrumed on said top member 15 for actuating said rack-bar, an intermediate vertical shaft located at the side of said support, a horizontal crank-disk secured to the upper end of said intermediate shaft, a pitman for connecting said rack-bar with 20 said crank-disk, said pitman being detachable at one end, and a fly-wheel rotatively mounted below said support and driven from said intermediate shaft.

5. Operating mechanism for washing machines and the like comprising, in combination 25 with a support including a vertically

swinging top member, a vertical operating shaft capable of rotary reciprocatory movement carried by said top member, a gear secured to said shaft, a reciprocable rack-bar 30 carried by said top member in mesh with said gear, a hand-lever fulcrumed on said top member for actuating said rack-bar, an intermediate vertical shaft located at the side of said support, a horizontal crank-disk secured to the upper end of said intermediate shaft, a pitman for connecting said rack-bar with said crank-disk, said pitman having detachable connection with said crank-disk, a horizontal fly-wheel below said support, and 35 a pulley and belt speed-increasing connection between the lower end of said intermediate shaft and said fly-wheel.

In testimony, that I, claim the foregoing as my invention I affix my signature in the 40 presence of two witnesses, this 16th day of September A. D. 1912.

JOHN EDENS.
